PROCESS OF MAKING FIBER FILLED WOVEN PRODUCT

Original Filed May 10, 1927 2 Sheets-Sheet 2

UNITED STATES PATENT OFFICE

CHARLES H. CROWELL, OF FAIRVILLE, PENNSYLVANIA

PROCESS OF MAKING FIBER-FILLED WOVEN PRODUCT

Application filed May 10, 1927; Serial No. 190,328. Renewed October 19, 1929.

The invention relates to a process for making a combined web of cloth and paper and more particularly to a process for making a fiber filled woven fabric.

According to the invention a web of suitable cloth may be adhesively secured to a web of suitable paper to form a single composite web, and a second web of cloth may be adhesively secured to the paper to form a double composite web, the single composite web being in a damp condition when the second cloth is applied. The paper web may be split to form two single composite webs, while the double composite web is in a damp condition.

The carrying on of the several operations while the materials are not fully dried, allows the process to be sped up and also promotes even and uniform splitting of the paper. Furthermore, according to the invention the several operations may be carried on without any undesirable effects from wrinkling and without causing other imperfections in the product.

A further feature of the invention lies in the subsequent treatment of a single or double composite web by suitable calendering rolls under suitable conditions of heat and pressure to thoroughly and intimately press the fibers of the paper into the fabric of the cloth to make in effect a fiber filled woven product. Further features of the invention lie in the detailed steps which are used to carry out the invention.

Various other features and advantages of the invention will be apparent from the following particular description and from an inspection of the accompanying drawings.

Although the novel features which are believed to be characteristic of this invention will be pointed out with particularity in the claims appended thereto, the invention itself, as to its objects and advantages, the mode of its operation and the manner of its organization may be better understood by referring to the following description taken in connection with the accompanying drawings forming a part thereof, in which

Figs. 1-4 inclusive, represent diagrammatically the steps in combining and splitting the several webs in the improved process,

Fig. 5 represents, diagrammatically, the steps in combining a composite web of cloth and paper to form a fiber filled woven fabric.

Referring now to the drawing, in which the steps and apparatus are indicated more or less diagrammatically, and more particularly, to Fig. 1, a web of suitable paper 1 has applied thereto suitable adhesive on one side thereof by means of suitable rolls indicated by 2.

A web of light open-mesh cloth 3, such as gray goods, may be applied to the adhesive covered surface of the paper web by passing between suitable rolls 4 to form a single composite web 5, the composite web being preferably passed through a drying room 6, to preferably partially dry the composite web, so that it is delivered in a damp condition. The composite web 5 has then applied thereto additional adhesive on the free side of the paper, and a second web 8 of cloth is applied to this side of the paper by means of suitable rolls 9 to form a double composite web 10, this web being passed through a drying room 11 to preferably partially dry the double composite web so that it is delivered in a damp condition.

The double composite web may then be passed between splitting rolls 12, and the paper may be split, as illustrated diagrammatically, forming composite webs 13 and 14.

By using the proper weight and kind of paper, adhesive may be applied thereto, the cloth web combined therewith, and the single composite web 5 may be delivered from the drying room damp, without wrinkling and without having any other imperfections. The damp delivery speeds up the processing considerably, since the composite web 5 may be passed through the drying room very quickly. Since the composite web 5 is delivered from the drying room without wrinkles the adhesive from the adhesive roll 7 may be applied and the second web of cloth 8 may be applied without causing wrinkles or other imperfections in the web. The delivery of the double composite web 10 from the drying room in a damp condition, also speeds up the processing.

Delivering the single composite web 5 from

the drying room in a damp condition also has the additional advantage of preventing over-drying, which impairs the quality of the product considerably.

For economical reasons it is desirable to use the lightest weight paper possible, which will not cause expansion wrinkles or other imperfections in the composite web, when the large amount of adhesive is applied. It has been found that a good grade of kraft paper of weight 45 pounds to the ream of 480 sheets 24" x 36" in size gives good results. This paper is particularly free from imperfections in the texture thereof, and does not wrinkle when the single composite web is delivered damp, and the second adhesive is applied to the paper web while in a damp condition.

By using the proper weight paper, and delivering the single composite web and the double composite web damp the paper splits unequally but readily and very evenly and uniformly, the heavier split web adhering to the cloth web first applied, while the lighter split web adheres to the cloth web secondly applied.

It has been found that in some cases a lighter paper web may be used, as for instance, a 35 pound paper under the same conditions of processing as above described. It has been found that this weight splits evenly and uniformly into approximately equal halves.

The adhesive used may be any of the adhesive materials used in the art, such as a paste having a flour base or a starch base, or any of the adhesive gums. If a waterproof adhesive is desired, gilsonite, asphaltum or the like may be used.

Referring now to Fig. 2, the single composite web 14 having the heavier split paper web, and which may be quite dry is passed through further adhesive rolls 15, where adhesive is applied to the exposed side of the paper. Then a third web 16 of cloth is applied to the adhesive between suitable rolls 16 and the resultant double composite web 17, may be passed through a drying room 18 and delivered preferably damp to paper splitting rolls 19, on which the paper is split into equal webs 20 and 21, the paper splitting evenly and uniformly. Thus it will be seen that using a sufficiently heavy paper originally prevents wrinkling and other imperfections. Delivering the paper web with cloth applied to both sides damp automatically allows ready, even and uniform splitting. Furthermore, no wrinkling occurs when the third adhesive and cloth web is applied to the heavier part of the split paper because the first backing cloth and adhesive prevents this action.

The above process thus far provides what has been termed, for convenience, a single composite web, that is, a cloth backing with a single layer of split paper applied thereto.

If it is desired to produce a double composite web having a paper coating on each side, further processing is necessary.

Referring now to Fig. 3 an additional paper web 22 is provided of the lightest weight which will not wrinkle, and which may be of the same weight as paper web 1, and adhesive is applied to one side thereof, by the adhesive rolls 23. The paper is passed between suitable rolls 24 with a single composite web such as, for instance, the composite web 20 or 21, which it is desired to modify into a double composite web. The double composite web 25 with the unsplit paper on one side and the split paper on the other side, may be passed through a suitable drying apparatus, 26, from which it may be delivered damp, after which adhesive may be applied to the exposed side of the unsplit paper web, by adhesive rolls 27.

A second single composite web such as composite web 20 or 21 which it is desired to make double, is applied to the adhesive between suitable rolls 28 to form a multiple composite web 29 which may be passed through suitable drying apparatus from which it may be delivered damp. The multiple composite web 29 is then passed through splitting rolls 31 where the unsplit central web 22 is split into a light layer forming part of the double composite web 32 and a heavier layer forming part of the double composite web 33, the unsplit paper splitting evenly and uniformly but unequally as described in Fig. 1. It will be seen that the one composite web 32 comprises a cloth backing with equal layer of split paper on each side. This composite web may be set aside for further processing as explained hereinafter.

Referring now to Fig. 4, the other double composite web 33 with the unequal layers of split paper may be passed through adhesive rolls 34 to apply adhesive to the heavier paper layer. Another web of cloth 35 may be applied to the adhesive by means of suitable rolls 36 and to form a multiple composite web 37, this web, if desired, being passed through suitable drying apparatus 38 from which it is preferably delivered damp. The heavier paper web is split by means of splitting rolls 39, this web splitting equally to form a double composite web 40 having an equal layer of paper on each side, and a single composite web 41 having the desired layer of paper on one side.

After either a single composite web is made or a double composite web, according to which is desired, each web having the desired thin layer of split paper, these composite webs may be further processed as follows to thoroughly fill the cloth with the fibers of the paper. The composite web including a layer of paper and a layer of cloth which is subjected to further treatment as explained hereinafter may be produced by the process hereinbefore

described or by any other process used for the purpose of forming a composite web including a layer of cloth and a layer of paper.

Referring to Fig. 5, in which the further processing is shown as applied to a single composite web, the composite web 50 may be passed between a suitable wetting roll 60 and a companion roll 51 where the paper side is saturated with wetting mixture.

10 The wetting roll 60 contacting the paper side of the composite web 50 shown as the upper roll in the drawing may be made of rubber and has the wetting mixture applied thereto. Suitable regulating means may be provided to regulate the amount of wetting mixture applied to the rubber roll. The regulating means may be such that an infinitesimal amount may be applied if desired.

15 If desired, the wetting mixture may have suitable sizing, such as potato starch, and suitable waxes incorporated therewith. This arrangement makes the paper side of the composite web much more water repellent, and places the composite web in a much better condition for applying the adhesive coating which is applied later in the process, as hereinafter explained. The mixture containing the starch sizing and waxes has good penetrating qualities, especially if the mixture be applied hot.

20 The composite web 50 is then passed through a supercalendering machine 52, the calendering machine being indicated diagrammatically. The calendering machine may comprise a plurality of rolls between which the web is squeezed. Alternate rolls may be of cast iron which are steam heated, while the intermediate rolls may be covered with paper or cloth. The composite web 50 is passed between these rolls, as shown, with the paper side facing the steam heated rolls to prevent sticking. The rate of travel of the composite web and the distance between the wetting roll 60 and the super-calender 52 is 25 preferably such as to allow ample time in which the wetting mixture can thoroughly spread and penetrate the composite web.

25 By means of this calender, in which the composite web 50 is subjected to both heat and pressure, the paper web is pressed into intimate relation with the fabric of the cloth. The first rolls of the calender thoroughly squeeze the wetting mixture into both the adhesive and the cloth. The wetting and calendering produce a homogeneous mass of fiber, wetting mixture, adhesive and woven fabric, making a fiber filled woven fabric. The fibers of the paper are passed into intimate relation with the threads of the cloth 30 to fill the cloth. The calender may deliver the product in practically dry condition. The strength of the combined web of cloth and split paper is materially increased over the old combined webs made by old processes 35 which merely attain more or less a coating

relation between the paper and the cloth. Each portion of the web is in contact with the rolls continuously from its entry into the calender to its exit therefrom. No shrinking occurs throughout the entire process. The process uses the paper after it has been felted and made into the most even and uniform product possible.

70 The double composite webs may be treated in the same manner as the single composite web to obtain the intimate relation between the paper and the cloth. Similarly the multiple composite webs may be treated in the same manner, if desired. After the paper and cloth webs have been pressed together to form a fiber filled woven fabric, the resultant web may be further treated. Layers of attaching adhesive may be applied to either one or both sides either over the entire area 75 or in the form of adhesive strips. Furthermore, one or both sides may be colored or coated with wax or other material which may be necessary to give the desired finish. The attaching adhesive is preferably applied to the more pronounced paper side of a single composite web.

80 If colored material is desired, the cloth may be colored or dyed before combining with the paper, and if both sides are desired to be alike, colored paper may be used.

85 The fiber filled woven product according to the invention is superior to any paper coated fabric heretofore produced. The surfaces are superior for coating and as printing surfaces, waterproof or otherwise, such as used for the leaves in children's books, shade cloths, cloth bags, bale wrapping etc. In addition, the edges cut evenly and there is no unraveling, nor is there any tendency for the edges to curl. The final product may be in the form 90 of flat sheets or in the form of bundle rolls.

95 Although certain novel features of the invention have been shown and described and are pointed out in the annexed claims, it will be understood that various omissions, substitutions and changes in the several steps of the process and in its operation may be made by those skilled in the art without departing 100 from the spirit of the invention.

110 What is claimed is:

115 1. The process of making composite fabric which comprises adhesively securing a web of light cloth to one side of a web of paper which will not wrinkle, allowing said webs to remain damp, adhesively securing a second web of light cloth to the other side of said paper web while said paper web is damp, and splitting said paper web while said paper web is damp.

120 2. The process of making composite fabric which comprises adhesively securing a web of light cloth to one side of a web of paper, allowing said webs to remain damp, adhesively securing a second web of light cloth to the other side of said paper web, and splitting 125

said paper web while said paper web is damp.

3. The process of making composite fabric which comprises adhesively securing a web of light cloth to one side of a web of paper sufficiently heavy not to wrinkle, partially drying said webs, adhesively securing a second web of light cloth to the other side of said web of paper, partially drying the resultant product, splitting said paper to form 10 a first composite fabric having a relatively light web of paper and a second composite fabric having a relatively heavy web of paper, adhesively securing a third web of light cloth to the paper of said second composite fabric, partially drying the resultant product and splitting said relatively heavy web of paper.

4. The process of making composite fabric which comprises securing a web of light 20 cloth to one side of a web of paper, securing a second web of light cloth to the other side of said web of paper, splitting said paper to form a first composite fabric having a relatively light web of paper and a second composite fabric having a relatively heavy web 25 of paper, securing a third web of light cloth to the paper of said second composite fabric, and splitting said relatively heavy web of paper.

30 5. The process of making composite fabric which comprises adhesively securing a web of light cloth to one side of a web of paper free from imperfections and sufficiently heavy not to wrinkle, allowing said webs to remain 35 damp, adhesively securing a second web of light cloth to the other side of said paper web, and unequally splitting said paper web while said paper web is damp, into two single composite webs having uniform coats of split 40 paper, one coat being heavier than the other.

6. The process of making composite fabric which comprises securing a web of light cloth to one side of a web of paper, securing a second web of light cloth to the other side of 45 said paper web, and unequally splitting said paper web into two single composite webs having uniformly even coats of split paper.

7. The process of making double composite fabric which comprises securing the cloth 50 side of a single composite web to one side of a paper web, securing the cloth side of a second single composite web to the other side of said paper web, unequally splitting said paper web to form two double composite webs, one having a heavier coating of paper 55 than the other, securing a web of cloth to said heavier coating, and splitting said heavier coating to form composite webs.

8. The process of making composite fabric 60 which comprises securing the cloth side of a composite web to one side of a paper web, securing a cloth web to the other side of said paper web and splitting said paper web to form two composite webs.

65 9. The process of making double composite

fabric which comprises securing the cloth side of a single composite web to one side of a paper web, securing the cloth side of a second single composite web to the other side of said paper web and splitting said paper web 70 to form two double composite webs.

10. The process of making composite fabric which comprises securing webs of cloth to the opposite sides of a web of paper, dampening said paper web and splitting said paper web while it is damp into two composite webs each comprising a cloth layer having a uniform layer of prefelted fibers 75 thereon.

In testimony whereof I have hereunto set 80 my hand.

CHARLES H. CROWELL.
